CHARLES P. RICKER AND WINTHROP L. GUILD, OF DIXFIELD, MAINE, ASSIGNEES TO
DIXFIELD TOOTHPICK COMPANY, OF DIXFIELD, MAINE, A CORPORATION OF MAINE.

PACKAGING-MACHINE FOR TOOTHPICKS AND SIMILAR ARTICLES.

1,203,129.

Specification of Letters Patent.

Patented Oct. 31, 1916.

Application filed November 22, 1915. Serial No. 62,762.

To all whom it may concern:

Be it known that we, CHARLES P. RICKER and WINTHROP L. GUILD, citizens of the United States, and residents of Dixfield, in the county of Oxford and State of Maine, have invented new and useful Improvements in Packaging-Machines for Toothpicks and Similar Articles, of which the following is a specification.

10 This invention relates to machines for packaging toothpicks and similar articles, and more particularly to the provision of efficient means in such machines for receiving the toothpicks or other articles according to the common practice in a confused mass, and quickly and accurately arranging them in the required position for boxing, *i. e.*, in substantial parallelism with their ends in the same vertical plane, and passing 20 them on in this position for actual boxing, whether such boxing be performed manually or by suitable mechanism.

Referring to the drawings which illustrate an embodiment of the invention,—Figure 1 is a front view of our improved machine; and Fig. 2 is a side view thereof.

25 A is a hopper, preferably of the form shown, having an open top and a restricted delivery opening a' in its bottom of slightly greater length than that of the articles being operated upon. The front A' is of transparent material, preferably glass, and is removably secured as by bolts B, having nuts B', passing through the projecting ends of 30 straps C on the side walls of the hopper. Preferably cushions D of felt or other suitable material are located between the edges of the front A' and the straps C to prevent chipping or breaking of the glass by reason 35 of the jarring of the hopper hereinafter described. Mounted in said hopper A are a plurality of movable partition walls E, preferably of sheet metal, dividing the hopper into a plurality of compartments. One or 40 more of the said partition walls E is secured to the back wall of the hopper, near the top thereof in any suitable manner, as by plugs S (Fig. 1) rigidly mounted on said back wall and having grooves into which the said 45 partitions fit. Shelves or ledges F are secured to each of such partition walls and also to the side walls of the hopper, so that each compartment has a series of shelves or ledges extending therein and arranged in 50 staggered relation.

55 G is a support adapted to be secured to the machine frame having forwardly extending arms G' provided with substantially flat top faces G². Fast on the back of the hopper A is a strap H having forwardly extending arms H' pivotally secured to the arms G' of the support G in any suitable manner, as by pintles I. Preferably each of such arms G' has a socket or recess J adapted to receive a spring K, one end of which bears 60 against the pintle I thus cushioning and preventing the breaking of said pintles by the jarring of said hopper. The said arms H' are provided with lateral flanges H² extending over the tops G² of the arms G', and said flanges are provided at or near each end with a stop or projection L, preferably in the form of set screws as shown, which pass through said flanges and project from their lower faces.

75 The operation is as follows: Any suitable mechanism such as an eccentric and its connections shown in Fig. 1, rocks the hopper A on its pintles I. This rocking movement is not only short and sharp but the rapid 80 impact of the projections L on the faces G² results in a very considerable jarring of the hopper each time a pair of projections strikes said faces. The toothpicks or other articles are fed into the open top of the 85 hopper in a confused mass and fall onto the uppermost ledges or shelves F. Because of the jarring and rapid backward and forward movement of the hopper in the direction of the length of the toothpicks, which causes 90 them to strike alternately against its front and back, the mass falls in a zig-zag path from one ledge to another, the individual toothpicks being brought into closely packed 95 parallelism with their ends in the same vertical plane until they come to the bottom and pass out through the discharge opening a' which, as above described, is of slightly greater length than the toothpicks.

100 It not infrequently happens that the downward movement of the mass within the hopper is arrested by the wedging action of a broken toothpick, splint or the like, rendering the machine partly or wholly inoperative until the mass can again be started downward. To obviate this difficulty a bar M is provided, connected with the partitions E which are secured to the back wall of the hopper by connections M' passing through slots a in said back wall below the point 110

at which said partitions are secured to said back. Links N and N' connect said bar with a lever O pivoted on the support G. When the downward movement of the mass 5 is arrested for the reason above described, the operator observing the difficulty through the transparent front, swings the lever O rapidly from side to side, and this movement being communicated to the movable 10 partitions E shakes the mass within the hopper, bringing the broken toothpick or the like into proper position so that the mass may again move downward. In some instances of stoppage of the movement of the 15 mass by reason of a broken toothpick or the like, it is desirable to insert a suitable instrument directly into the hopper to bring a particular toothpick into proper alignment. For this purpose the walls of the 20 hopper are provided with a series of apertures A², as best shown in Fig. 1, opposite the several spaces between shelves through which a suitable instrument may be readily inserted directly into the mass.

25 Our improved machine above described is simple in construction and operation, and it has proved in service a most efficient means for assembling toothpicks and similar light wooden articles in proper position to be 30 passed on to the measuring and boxing apparatus.

We claim:

1. In a device of the class described, means for arranging articles massed at random 35 comprising a hopper having front and back walls, partitions from wall to wall in said hopper adapted to determine a zig-zag path for articles falling through the hopper, means for oscillating the hopper in a direction angular to said walls, and means for violently stopping motion of said hopper in each direction, whereby articles falling 40 through said hopper are thrown violently and repeatedly against each wall.
2. In a device of the class described, means for arranging articles massed at random 45 comprising a vertical hopper having front and back walls diverging toward the top, partitions from wall to wall in said hopper adapted to determine a zig-zag path for articles falling through the hopper, means for oscillating the hopper in a direction angular to said walls, and means for violently stopping motion of said hopper in 50 each direction, whereby articles falling through said hopper are thrown violently and repeatedly against each wall and brought into parallelism in a mass little thicker than the length of each article.
3. A machine of the class described, comprising a frame, a hopper through which the material operated upon progresses under gravity, arms connected with said hopper 55 and pivotally secured to said frame all on a common axis, and means to rock said hop-

per in directions transverse to the progress of the material, said arms having projections adapted, upon the rocking of said hopper, to engage said frame at the ends of each rocking motion, whereby to jar said hopper 70 in a direction transverse to the progress of the material.

4. A machine of the class described, comprising a frame, a hopper, arms connected with said hopper, a pair of pintles passing 75 through said frame and arms and having movable bearings, means to rock said hopper, said arms adapted upon the rocking of said hopper to engage said frame.

5. A machine of the class described, comprising a frame, a hopper, arms connected with said hopper, a pair of pintles passing through said frame and arms, having movable bearings and cushioned against jar, means to rock said hopper, said arms adapted 85 upon the rocking of said hopper to engage said frame.

6. A machine of the class described, comprising a frame, a hopper, arms connected with said hopper, a pair of pintles passing 90 through said frame and arms whereby said hopper is pivotally mounted on said frame, recesses in said frame, springs in said recesses and engaging said pintles, means to rock said hopper, said arms adapted upon the rocking of said hopper to engage said frame.

7. A machine of the class described, comprising a frame, a hopper, arms connected with said hopper, a pair of pintles passing 100 through said frame and arms whereby said hopper is pivotally mounted on said frame, recess in said frame, springs in said recesses and engaging said pintles, means to rock said hopper, and said arms having projections adapted upon the rocking of said hopper to engage said frame.

8. A machine of the class described, comprising a frame having forwardly extending arms, a hopper having arms pivoted to said frame arms, whereby said hopper is pivotally mounted on said frame, means to rock said hopper and said hopper arms having flanges extending over said frame arms and provided with projections near each end 115 thereof adapted upon the rocking of said hopper to engage said frame arms.

9. A machine of the class described comprising a frame, a hopper pivoted on said frame and having a glass front, means connected with the opposite side walls of said hopper and engaging said front removably to secure said front in operative position, cushions between said securing means and said front, means to rock said hopper, and means to jar said hopper during the rocking thereof.

10. A machine of the class described comprising a frame, a hopper mounted on said frame and having a movable partition divid-

ing it into compartments having shelves arranged in staggered relation therein, means to rock said hopper, and means operable independently of said rocking means to move said partition from side to side.

11. A machine of the class described comprising a frame, a hopper mounted on said frame and having a movable partition dividing it into compartments having shelves arranged in staggered relation therein, means to rock said hopper, and means operable in-

dependently of said rocking means comprising a pivoted lever and connections between said lever and said partition to move said partition from side to side.

15

Signed by us at Dixfield, Maine, this eighteenth (18) day of November, 1915.
